US00D344317S

United States Patent [19]Petersheim*Patent Number: Des. 344,317*Date of Patent:  Feb. 15, 1994*[54] COMBINED SLIDE AND PLAY ENCLOSURE*[75] Inventor: Richard J. Petersheim, Charlotte, N.C.[73] Assignee: Restaurant Technology, Inc., Oak Brook, Ill.[] Term: 14 Years*[21] Appl. No.: 834,506*[22] Filed: Feb. 11, 1992*[52] U.S. Cl. .... D21/244*[58] Field of Search ..... 472/48, 92, 116, 117, 472/126, 134, 136, 137; 446/70, 168, 220, 221, 106, 110, 476; D21/240-252*[56] References Cited*U.S. PATENT DOCUMENTS

D. 251,132 2/1979 Reverchon ..... D21/242 X
D. 328,119 7/1992 Matsch D21/244
D. 330,741 11/1992 Matsch D21/242

D. 330,742 11/1992 Matsch D21/242
779,329 6/1905 Thompson ..... 472/136 X

OTHER PUBLICATIONS

Design 314, Feb. 1975, p. 55.

Euro-Matic Ltd. 1989, as shown.

Maxico Forge 16-1984, p. 49, as shown.

*Primary Examiner—Prabhakar G. Deshmukh
Attorney, Agent, or Firm—Jenner & Block*

[57] CLAIM

The ornamental design for a combined slide and play enclosure, as shown.

DESCRIPTION

FIG. 1 is a perspective view of a combined slide and play enclosure showing my new design;
FIG. 2 is a left side elevation thereof;
FIG. 3 is a top plan view thereof;
FIG. 4 is a front elevation view thereof;
FIG. 5 is a rear elevation view thereof; and,
FIG. 6 is a right side elevation thereof.

FIG. 1

FIG. 2

FIG. 3FIG. 4FIG. 5

FIG. 6